WIRE DIAMETER GAUGE

Roger B. Kerr, Topsfield, Mass., assignor to General
Electric Company, a corporation of New York

Filed June 28, 1963, Ser. No. 75,571

Term of patent 14 years

(Cl. D52—6)

FIG.2

FIG.1

FIG. 3

FIG. 1 is a perspective view of a wire diameter gauge of my new design;

FIG. 2 is a rear view of the wire diameter gauge of my new design; and

FIG. 3 is a top plan view of the wire diameter gauge of my new design.

The undisclosed side of the wire diameter gauge is substantially the same in appearance as the side shown.

The essential features of the design reside in the portions shown in full lines. The fragmentary broken line portion of the rod shown in FIGURE 1 is depicted for illustrative purposes only.

I claim:

The ornamental design for a wire diameter gauge, as shown and described.
